UNITED STATES PATENT OFFICE

92,981

DESIGN FOR A FOOD CONTAINER

Lewis H. Scurlock, Chicago, Ill.

Application October 27, 1933, Serial No. 49,571

Term of patent 14 years

To all whom it may concern:

Be it known that I, LEWIS H. SCURLOCK, a citizen of the United States, and resident of Chicago, in the county of Cook and State of Illinois, have invented a new, original, and ornamental Design for a Food Container, of which the following is a specification, reference being had to the accompanying drawing, forming a part thereof:

Fig. 1 is a plan view of a food container showing the new and ornamental design.

Fig. 2 is a side elevation of said food container. The device of my design comprises the several

elements shown in solid black lines in the drawing, combined with a base shown in dotted lines. The dominant features of the design are shown in the solid black lines.

The ornamental design comprises the circular middle effect shown, surrounded by the arcuate sections forming the border of the design, shown in Figs. 1 and 2 of the drawing.

I claim:

The ornamental design for a food container, as shown and described.

LEWIS H. SCURLOCK.
